(57) **CLAIM**

I claim the ornamental design for a baton, as shown and described.

DESCRIPTION

FIG. 1 is a side view of the baton showing my new design, with the design being shown in a compressed state;

FIG. 2 is a perspective view thereof, with the front and side being a mirror image;

FIG. 3 is a perspective view shown in an expanded state, with the front and side being a mirror image; and,

FIG. 4 is a rear view.
